(57) **CLAIM**

We claim the ornamental design for a top of a deck member, as shown and described.

DESCRIPTION

FIG. 1 is a fragmentary perspective view of our design;

FIG. 2 is a fragmentary top view;

FIG. 3 is a fragmentary bottom view;

FIG. 4 is a fragmentary left side view;

FIG. 5 is a front view, the back being a mirror image thereof; and,

FIG. 6 is a fragmentary right side view.

The top of a deck member is broken on the end to indicate indeterminate length.
